UNITED STATES PATENT OFFICE.

ANDREWS ALLEN, OF CHICAGO, ILLINOIS.

SASH-OPERATING DEVICE.

1,055,593.

Specification of Letters Patent. Patented Mar. 11, 1913.

Application filed September 20, 1909. Serial No. 518,488.

To all whom it may concern:

Be it known that I, ANDREWS ALLEN, a citizen of the United States, residing at Chicago, in the county of Cook and State of Illinois, have invented certain new and useful Improvements in Sash-Operating Devices, of which the following is a specification.

This invention relates to means for operating and locking casement windows, screens, shutters, and the like, and has for its object to provide a device which will enable a casement window, or other sash or shutter hinged at one edge, to be opened by 10 a direct outward thrust; to provide an operating mechanism which will be readily adapted to casement windows of the like where screens, when employed, are necessarily placed on the inside of the hinged 15 sash; and to provide an operating device which will automatically lock the window and also the screen when in the closed position. To accomplish these and other desirable advantages which will appear in 20 connection with the particular description of the invention, I construct the operating mechanism in the form of a jointed bar, the joints being of unequal length, the shorter one having a pivotal connection with an attaching member or bracket for securement 25 to the sash, and the longer one having its inner end preferably fashioned to provide a finger hold and guard. Both members of the operating bar are preferably provided 30 with perforations for the passage of a locking pin. A guide member or keeper is adapted to be secured to the window sill and is provided with a guide slot through 35 which the operating bar reciprocates, and 40 with a vertical perforation for the locking pin.

In the accompanying drawings—Figure 1 is a sectional elevation through the lower portion of a casement window, a screen, and 45 the window sill and water table, showing the operating device in side elevation and in closed and locked position, and also by dotted lines in open position; Fig. 2 is a perspective view of the device detached from the 50 window; Fig. 3 is a sectional detail plan view of the guide keeper and operating bar, the latter being broken away, the dotted lines showing different positions of the bar; Fig. 4 is a transverse sectional view through 55 the window sash, screen, one side frame, the sill, water table, the operating device show-

ing in plan view; Fig. 5 is a detailed view showing a modification in the construction of the hinge joint of the locking bar; and Fig. 6 is a fragmentary view of the upper 60 end of the screen showing a hinge therefor.

In the drawings, 7 indicates the lower frame bar of a casement window.

8 indicates the window sill and 9 the water table.

10 represents the frame of a fly-screen and 11 one of the hinges whereby the screen is suspended from its upper end.

It will be understood that the window may be hinged at one edge as shown at 12 70 (Fig. 4).

Usually in casement windows the sill is very narrow and the space allowed for the mounting of the window sash and the screen is restricted; therefore, it is important to 75 provide an operating means for the window sash which is adapted to these narrow limits.

My improved operating device is shown complete in Fig. 2, wherein 14 and 15 represent two plates constituting a guide-keeper, and which as shown are formed separately for convenience of construction, but which might be made integral. The member 14 has an upstanding flange 14^a and a horizontal shelf-like portion 14^b.

The flange 14^a is parted at its middle to permit the passage of the operating bar, the parted portions 14^c being arranged at an angle and converging rearwardly to constitute guides for the operating bar; on the extremities of the portion 14^c the operating bar fulcrums when the window is opened wide. The keeper may be attached at either side of the window. The shelf-like portion 14^b and the base member 15 have registering perforations for a locking pin 16 and other perforations 14^d for fastening screws. The operating bar is composed of two members 17, 18 hinged together by a pin 19, the member 18 having a 100 knuckle 18^a, as shown in Fig. 2. This knuckle may, as shown in Fig. 5, be extended, the slot in the member 17 being correspondingly lengthened, so that the extension will abut against the edge of the shelf 14^b, thereby affording a lock for the screen and window when closed and the member 18 falls into vertical position as indicated in 105 Figs. 1 and 2. The outer end of the member 17 is pivotally connected to the bracket 110 plate 20, which will be secured by means of screws to the bottom bar 7 of the window

sash. The keeper projects beneath the screen, the lower bar 10 of which may be cut away to permit its passage.

- With the parts constructed and arranged 5 as above described, the window sash may be opened and locked in any desired position of adjustment by a straight thrust of the operating bar, and the latter during the early part of its movement being extended 10 in a straight line. When moved to the full extent the bar will assume angular positions such as indicated by the dotted lines in Fig. 3, the degree of angularity depending upon the extent of the movement; but the bar is 15 operated by a straight thrust and is guided by the members 14^a at all times regardless of the extent of the movement. The bar is locked in the attained position by the insertion of the pin 16 through the aperture of 20 the base plate inside of the screen, the locking pin passing through one of the apertures of the bar 18. This bar is preferably provided at its free extremity with a finger piece 18^b and a guard 18^c affording convenient means both for moving the bar and 25 protecting the fingers against injury. These parts may be formed in other ways, as, for example, by bending the end of the bar to circular form. When the member 18 is in 30 the pendent position indicated in Figs. 1 and 2, the device would be locked since it would be difficult to apply sufficient force from the outside to raise this member and draw it through the keeper. I 35 prefer, however, to extend the member 18^a as shown in Fig. 5 so as to form a positive lock.

My invention is adapted to shutters and to other structures of the sort whether 40 hinged at the longitudinal edge or at one end, but is particularly adapted for use in connection with casement windows which necessitate the mounting of the screen inside of the window, and the device may be applied 45 indifferently to windows hinged at one side or the other without modification of its structure.

Jointing the operating rod has several advantages, as follows: The device may be 50 adapted to windows of any width and to different widths of sills; the rod when very long would be objectionable because it would be in the way if made in a single piece; and by jointing the rod the inner member affords 55 an efficient lock.

Obviously, structural variations may be made within the scope of my invention, as, for example, in the proportional length of the two members of the operating bar; in the specific character of the locking pin and 60 perforations; and in the form of the guide. The guide may be countersunk in the window sill or covered by a false sill to avoid cutting the screen sash.

65

I claim:

1. In a window sash operating device, the combination of a jointed operating rod having a plurality of locking apertures therein, a guide member having an aperture adapted to register with any of said rod apertures, a pin in two of said registering apertures whereby said rod and guide member are locked together, and a pair of guides proper constituting part of said guide member having free edges contacting opposite sides of 75 said rod in a vertical plane substantially through said pin, whereby said pin alone holds said rod in locked position and whereby a close sliding connection is maintained between said guides proper and said rod in 80 varying angles of the rod, substantially as described.

2. In a window sash operating device of the class described, the combination of an operating rod, a guide member, said guide 85 member having an end portion comprising a base and a cover and an upstanding wall between said base and cover, said wall being divided centrally and the divided parts thereof bent apart to form guides proper, 90 said rod being in sliding contact with the edges of said guides proper, said base and cover portions having registering apertures substantially in the vertical plane of the ends of said guides proper, said rod having 95 apertures adapted to register with said guide member apertures, and a pin locking the guide member and rod together, the arrangement being such that a tight connection exists between the ends of said guides and said rod in any operating angle of said rod, and whereby said ends may be bent into engagement with said rod to take up wear, and whereby said guides proper are free from binding action of said rod, substantially 100 as described.

105 ANDREWS ALLEN.
